OTHER PUBLICATIONS Design U.S. Appl. No. 29/383,683, filed Jan. 20, 2011; In re: Becker, entitled *Flask and Cap*.*Primary Examiner* — Ian Simmons*Assistant Examiner* — Dana L Meyrow(74) *Attorney, Agent, or Firm* — Alston & Bird LLP(57) **CLAIM**

We claim the ornamental design for a flask, as shown and described.

DESCRIPTION

FIG. 1 is a perspective view of a flask showing our new design;

FIG. 2 is a front elevation view thereof;

FIG. 3 is a top plan view thereof; and,

FIG. 4 is a bottom plan view thereof.

The unshaded areas shown in broken lines illustrate the portions of the design that form no part of the claim.
